UNITED STATES PATENT OFFICE

2,392,164

LAMP HOLDER

Elton A. Lindsay, Willoughby, Ohio, assignor to
General Electric Company, a corporation of
New York

Application October 11, 1944, Serial No. 558,197

12 Claims. (Cl. 173—328)

The present invention relates to lamp holders and particularly to lamp holders for incandescent lamps wherein the terminals of the lamp comprise two posts. Such lamps are known as "bipost" lamps. Usually, lamps of this type are high wattage lamps which means that the terminal posts of the lamps and the lamp holders are required to carry relatively large currents.

One object of my invention is to provide an improved lamp holder for a lamp of the bipost type which is simple in structure, insures positive electrical contact of large area between the terminal posts of the lamp and the lamp holder contacts so as to avoid overheating of the terminal posts and lamp holder contacts, and permits of the lamp being easily connected to and disengaged from the lamp holder without undue strain on the posts of the lamp.

A further object of my invention is to provide a lamp holder wherein the contact posts of the lamp are inserted into the lamp holder after which the lamp is turned through a short arc to complete the circuit between the contact posts of the lamp and the lamp holder contacts, the turning serving to effect tight contact between the current conducting parts.

Preferably, there is provided also means whereby when the lamp has been turned in the holder to bring the contact posts of the lamp into engagement with the terminal contacts of the lamp holder, the lamp is locked in position in the lamp holder and cannot be removed until it is turned back to its former position wherein its contact posts are out of engagement with the terminal contacts of the lamp holder.

Other objects of my invention and the advantages thereof will be pointed out hereinafter.

For a consideration of what I believe to be novel and my invention, attention is directed to the following specification and to the claims appended thereto.

In the drawings:

Fig. 1 is a sectional view of a lamp holder embodying my invention, it being shown with the contact posts of a bipost lamp in position in the holder and connected to the lamp holder terminals; Fig. 2 is a sectional view taken on line 2—2, Fig. 1; Fig. 3 is a sectional view taken on line 3—3, Fig. 2, and showing a bipost lamp end adjacent to it; Fig. 4 is a detail view partly in section illustrating a part of the structure shown in Figs. 1 and 3; Fig. 5 is a face view taken on line 5—5, Fig. 1, looking in the direction of the arrows, and Fig. 6 is an exploded view showing the parts which go to make up the lamp holder.

Referring to the drawings, 1 indicates a base of suitable insulating material which in the present instance is shown as being round and adapted to be connected to a support 2 by screws 3 which extend through openings in the base and thread into tapped holes 4 in the support. The base comprises a side wall 5 and an end or bottom wall 6, the other end being open thus providing a well in the base. The inner surface of the side wall is shaped to provide an annular shoulder or ledge 7 spaced from the open end of the base and separated into two arcuate sections by diametrically opposed projections 8. Positioned in each arcuate section is an arcuate strip 9 of a material which provides a suitable wear surface, each strip being provided at its end with feet 10 which rest on shoulder 7 so that the strips are spaced from the shoulder. Strips 9 may be formed from a suitable metal. The feet are of a length such that the outer surfaces of the strips are about flush with the surfaces of the projections 8. The outer surfaces of the strips and the surfaces of the projections 8 thus forming a continuous annular ledge in the well spaced from the open end of the well. The arcuate strips 9 are wedge-shaped as shown clearly in Figs. 3, 4 and 6. Thus, there is provided in the side wall of the base at a point spaced inwardly from its open end two arcuate grooves 10°, the inner walls 30 of which are formed by the surface of shoulder 7 and the outer walls of which are formed by the inner surfaces 11 of the strips 9 which are in the form of cam surfaces. Mounted in openings in bottom wall 6 are stationary contacts 35 each having a head 12 and a tongue 13 which projects from the head and is adapted to receive a screw 14 for connecting an electrical wire to the contact. The inner surface of end wall 6 is shaped to provide cam surfaces 15 which slope upward toward the top surfaces of heads 12, terminating flush with the top surfaces of the heads as shown clearly in Fig. 3. Thus, the top surfaces of the heads 12 form in substance a continuation of cam surfaces 15. The cam surfaces 11 and 15 are substantially parallel with each other.

Positioned in the well of the base is a carrier comprising a cylindrical body 16 having a flange 17 which rests on the annular shoulder formed by the top surfaces of strips 9 and projections 8 and is adapted to turn thereon. In body 16 are two axially extending tapered recesses 18, the recesses being widest at their inner ends. The outer ends of the recesses terminate flush with the underside of flange 17 and through the body are

openings 19 in line with recesses 18 and adapted to have inserted through them the posts of a bipost lamp. Located in recesses 18 are split connectors 20 which are wedge-shaped and are provided with angularly extending outturned feet 21 which are positioned in the arcuate grooves 10^a. The outer surfaces of the feet ride against the cam surfaces 11 of the strips 9. The inner ends of connectors 20 are flat as is indicated at 22 and are adapted to be moved along the inclined surface 15 into engagement with the heads 12 of the terminal contacts. The flat ends insure contact over substantial areas. The two parts of the wedge-shaped connectors are provided with recesses 23 which form an opening which stands in line with openings 19 and are adapted to receive the posts of a bipost lamp. In body 16 beneath flange 17 is an annular groove 23^a in which edges of strips 9 are positioned, the strips being wider than shoulder 7.

The carrier is held in position in the base 1 by a bolt 24 which extends through a central opening in the carrier and through bottom wall 6 and receives on its lower end a nut 24^a, there being positioned between the bottom wall and the nut a suitable spring 25 and a washer 26. Thus, the carrier is held yieldingly in the base 1. Nut 24^a is tightened to bring flange 17 down tight against the shoulder on which it turns. However, the spring will permit the carrier to move slightly axially when the connectors 20 ride up on the tops of the contact heads 12.

The end of a known type of bipost lamp is shown in Figs. 1, 3 and 4. It comprises a glass envelope 27 and two contact posts 28 which project from the base of the lamp. The contact posts are undercut adjacent their inner ends to provide shoulders 29. This is a known type of bipost lamp construction now on the market. To lock the lamp in the lamp holder, the arcuate strips 9 are provided with projecting flanges 30 which are adapted to stand over shoulders 29. Turning movement of the carrier in the base is limited by feet 21 striking the ends of the arcuate grooves 10^a in the base. When the feet are at the one end of the arcuate grooves 10^a, the connectors 20 are positioned on the contact heads 12. The flanges 30 terminate short of the ends of the strips 9 at the one end so that when the feet 21 are at the other end of the arcuate grooves, the 50 posts 28 stand beyond the ends of the flanges 30.

Fig. 3 shows the parts of the lamp holder in a position to have a lamp inserted therein. At this time, the feet 21 are at one end of the grooves 10^a and the cam surface 11 has moved the connectors 20 downwardly relatively to the carrier so that they are loose in the cam-shaped recesses 18. At this time, the openings 19 are at the end of strips 9 at which the flange 30 is not present so that the posts of the lamp may be readily inserted through the openings 19 to positions between the two parts of the connectors 20. Now by turning the lamp, it and the carrier move the connectors up the inclined surfaces 15 which results in moving the connectors upwardly in 65 wedge-shaped recesses 18 to force the parts of the connectors into tight engagement with the posts; and at the end of the turning movement, the ends of the connectors 20 ride up onto the tops of contact heads 12. The posts are now tightly gripped between the parts of the connectors 20 which are wedged against them, and by reason of the spring 25, the ends of the connectors are held firmly in engagement with the top surfaces of heads 12 over a substantial area. Thus, there

is provided contacts of substantial area between the heads 12 and the connectors 20 and between the connectors 20 and the posts 28. As soon as turning movement of the lamp and carrier is started, shoulders 29 are moved under flanges 30, thus locking the lamp in the holder. The lamp cannot be removed from the holder until it is turned back to its original position wherein feed 21 engage the other ends of the arcuate recesses 10^a and shoulders 29 are brought out from under flanges 30. Thus, it will be seen that the lamp is always disconnected from the receptacle contacts when it is being inserted and removed.

The recesses 18 and the connectors 20 are tapered relatively to each other by amounts such that when the parts of the lamp holder are in positions for the posts of a lamp to be inserted therein, the two parts of the connectors are relatively loose permitting the posts to be readily inserted therebetween; and when the lamp and carrier are turned to move the connectors up the inclined planes 15, the axial movement of the connectors is sufficient to wedge the parts of the connectors tightly against the posts. The cam surfaces 11 serve to move the connectors axially downward when a lamp is turned to remove it from the lamp holder thus releasing the posts of the lamp from the grip of the connectors during such turning movement.

Flanges 30 are adapted to cover partially the openings 19 so that the posts of a lamp cannot be inserted through the openings 19 except at a time when the openings have been brought out from under the flanges.

By my invention, I provide a lamp holder which is relatively simple in structure, comprises few parts and is capable of being manufactured at low cost. At the same time, there is provided a lamp holder wherein the posts of a bipost lamp are tightly clamped over surfaces of substantial area thus enabling the passage of relatively large currents without overheating. This latter is a thing of substantial importance in a lamp holder of this type. The arrangement of the spaced cam surfaces effect positive clamping and unclamping of the post of the lamp when a lamp is inserted and removed from the lamp holder.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

1. A lamp holder for a bipost lamp comprising a base having a well and a pair of spaced terminal contacts in the well, a carrier in the well turnable about its axis, a pair of split connectors carried by the carrier adapted to receive between the parts thereof the posts of a bipost lamp and movable into and out of engagement with said terminal contacts by turning movement of said carrier, and means for moving the parts of the split connectors relatively to each other when the carrier is turned to cause them to clamp the posts of a bipost lamp inserted therebetween.

2. A lamp holder for a bipost lamp comprising a base having a well and a pair of spaced terminal contacts in the well, a carrier, in the well turnable therein about its axis, connectors car-

ried by the carrier for engagement with the posts of a bipost lamp and movable into and out of engagement with said terminal contacts by turning movement of said carrier, and means which moves said connectors to clamp the posts of a bipost lamp when the posts of a bipost lamp are positioned in engagement with them and the carrier is turned to bring the connectors into engagement with the terminal contacts.

3. A lamp holder for a bipost lamp comprising a base having a well and spaced terminal contacts, a carrier in the well provided with axially extending recesses, connectors for engagement with the posts of a bipost lamp positioned in and axially movable in said recesses, said carrier being movable in said well to move said connectors into and out of engagement with said terminal contacts, means defining a surface in said well which effects axial movement of said connectors when the carrier is turned to bring said connectors into engagement with said terminal contacts, and means whereby axial movement of said connectors causes them to clamp the posts of a bipost lamp.

4. A lamp holder for bipost lamps comprising a base having a well and walls which define in the well axially spaced circumferentially extending cam surfaces, a rotatable carrier in said well having axially extending tapered recesses, axially split wedge-shaped connectors in said tapered recesses having axially extending grooves into which the posts of a bipost lamp may be positioned, the ends of said connectors engaging said cam surfaces whereby when the carrier is turned about its axis the parts of the wedge-shaped connectors are moved axially in said tapered recesses to effect movement of such parts toward each other, and terminal contacts in said base with which said wedge-shaped connectors engage.

5. A lamp holder for a bipost lamp comprising a base having a well and spaced terminal contacts in the well, a carrier in the well provided with axially extending recesses, axially split connectors in said recesses between the parts of which the posts of a bipost lamp may be positioned, said carrier being turnable in the well to bring the split connectors into and out of engagement with said terminal contacts, and means for effecting axial movement of the split connectors in said recesses when the carrier is turned to bring the split connectors into engagement with the terminal contacts, surfaces of said split connectors and of said recesses being so shaped relatively to each other than axial movement of the split connectors in the recesses causes them to clamp the posts of a bipost lamp inserted therebetween.

6. A lamp holder for a bipost lamp comprising a base having a well, a carrier mounted in the well for turning movement therein, two part connectors carried by the carrier for engaging opposite sides of the posts of a bipost lamp, means whereby turning movement of the carrier in the base causes said connectors to clamp the posts of a bipost lamp, and terminal contacts with which said connectors engage.

7. A lamp holder for a bipost lamp comprising a base having a well and a pair of spaced terminal contacts in the well, a carrier in the well turnable therein about its axis, connectors carried by the carrier for engagement with the posts of a bipost lamp and movable into and out of

engagement with said terminal contacts by turning movement of said carrier, and means which moves said connectors to clamp the posts of a bipost lamp when the posts of a bipost lamp are positioned in engagement with them and the carrier is turned to bring the connectors into engagement with the terminal contacts, and means for locking a lamp in the holder when the connectors are in engagement with the terminal contacts.

8. A lamp holder for a bipost lamp comprising a base having a well provided with cam surfaces on its bottom wall, terminal contacts adjacent to said cam surfaces, a carrier rotatably mounted in said well having axially extending recesses, connectors adapted to engage said terminal contacts and the posts of a bipost lamp positioned in said recesses and movable axially therein by said cam surfaces when the carrier is turned therein, and means whereby axial movement of said connectors causes them to clamp the posts of a bipost lamp.

9. A lamp holder for a bipost lamp comprising a base having a well provided with cam surfaces on its bottom wall, terminal contacts adjacent to said cam surfaces, a carrier rotatably mounted in said well having axially extending recesses, connectors adapted to engage said terminal contacts and the posts of a bipost lamp positioned in said recesses and movable axially therein by said cam surfaces when the carrier is turned therein, means whereby axial movement of said connectors causes them to clamp the posts of a bipost lamp, and yielding means acting in an axial direction to force the ends of the terminal contacts and the connectors into firm engagement with each other.

10. A lamp holder for a bipost lamp comprising a base having terminal contacts mounted therein, a carrier mounted in the base for turning movement therein, connectors carried by the carrier for engagement with the posts of a bipost lamp and with said terminal contacts, said connectors being axially movable relatively to the carrier, cam surfaces for effecting axial movement of said connectors when the carrier is turned on the base and means whereby axial movement of said connectors causes them to clamp the posts of a bipost lamp.

11. A lamp holder for a bipost lamp comprising a base, a carrier rotatably mounted on the base having axially extending recesses, axially movable connectors in said recesses adapted to engage the posts of a bipost lamp, terminal contacts on the base, cam surfaces adjacent to said contacts up which said connectors ride into engagement with said terminal contacts when the carrier is turned on the base, and means whereby axial movement of said connectors causes them to clamp the posts of a bipost lamp.

12. A lamp holder for a bipost lamp comprising a base, split connectors carried by the base, terminal contacts carried by the base with which said connectors may be moved into and out of engagement, and means operated by the insertion of the posts of a bipost lamp into engagement with said split connectors and the movement of the connectors into engagement with the terminal contacts to cause them to clamp such posts.

ELTON A. LINSDAY.
